(57) **CLAIM**

The ornamental design for an exit sign and rotatable emergency lamp, as shown and described.

DESCRIPTION

FIG. 1 illustrates a perspective view of an exit sign and rotatable emergency lamp of an embodiment of the present invention.

FIG. 2 illustrates a front view of an exit sign and rotatable emergency lamp of an embodiment of the present invention. FIG. 3 illustrates a rear view of an exit sign and rotatable emergency lamp of an embodiment of the present invention. FIG. 4 illustrates a top view of an exit sign and rotatable emergency lamp of an embodiment of the present invention. FIG. 5 illustrates a bottom view of an exit sign and rotatable emergency lamp of an embodiment of the present invention. FIG. 6 illustrates a side view of an exit sign and rotatable emergency lamp of an embodiment of the present invention. FIG. 7 illustrates a perspective view of an exit sign and rotatable emergency lamp of an embodiment of the present invention.

FIG. 8 illustrates a perspective view of an exit sign and rotatable emergency lamp of a second embodiment of the present invention.

FIG. 9 illustrates a front view of an exit sign and rotatable emergency lamp of a second embodiment of the present invention.

FIG. 10 illustrates a rear view of an exit sign and rotatable emergency lamp of a second embodiment of the present invention.

FIG. 11 illustrates a top view of an exit sign and rotatable emergency lamp of a second embodiment of the present invention.

FIG. 12 illustrates a bottom view of an exit sign and rotatable emergency lamp of a second embodiment of the present invention.

FIG. 13 illustrates a side view of an exit sign and rotatable emergency lamp of a second embodiment of the present invention; and,

FIG. 14 illustrates a perspective view of an exit sign and rotatable emergency lamp of a second embodiment of the present invention.

The broken lines in the drawings illustrate environmental structure and form no part of the claimed design.
